UNITED STATES PATENT OFFICE.

ARTHUR E. HAUCK, OF NEW YORK, N. Y.; ADOLPH H. STEIN EXECUTOR OF SAID
ARTHUR E. HAUCK, DECEASED.

KEROSENE-BURNER.

1,381,707.

Specification of Letters Patent. Patented June 14, 1921.

Application filed August 17, 1920. Serial No. 404,096.

To all whom it may concern:

Be it known that I, ARTHUR E. HAUCK, a citizen of the United States, and a resident of the city of New York, county of Kings, 5 and State of New York, have invented a new and useful Improvement in Kerosene-Burners, of which the following is a specification.

The object of my invention is to provide a burner which may be inserted into an ordinary coal stove and placed on the grate thereof, or in any other suitable position, and will there operate so as to heat the stove in which it is placed in a manner which corresponds in all practical respects with the 15 heating which is normally done by the combustion of coal or gas. A further object is to provide a burner which may be used in any desired environment for any heating purpose where it may be applied.

These and other objects are accomplished 20 by my invention, some embodiments of which are hereinafter more particularly set forth.

For a more detailed description of my invention, reference is to be had to the accompanying drawings forming a part hereof, in 25 which

Figure 1 is a side elevation, partially in section, of my improved burner when made in the form suitable for a kitchen range 30 which normally burns coal or gas.

Fig. 2 is a plan view of the same, the parts being removed to reveal a structure that would otherwise be concealed.

Fig. 3 is a sectional view taken on the line 35 3—3 of Fig. 1 looking in the direction of the arrows.

Fig. 4 is a sectional view taken on the line 4—4 of Fig. 2 looking in the direction of the arrows.

Fig. 5 is a sectional view taken on the line 40 5—5 of Fig. 4 looking in the direction of the arrows.

Figs. 6 and 7 show a modified embodiment 45 of my invention suitable for taking the place of a gas heater at the base of a coil used for heating the ordinary hot water boilers of the house, Fig. 6 being a plan view and Fig. 7 a sectional view on the line 7—7 of Fig. 6.

Throughout the various views of the drawings, similar reference characters designate 50 similar parts.

My improved burner 1 in the embodiment shown in Figs. 1 to 5 inclusive, is mounted on suitable legs 2 which are adapted to rest 55 on a grate or any other suitable support and

these legs support the body 3 of the burner which is preferably in the form of one-half a cylinder at the bottom with closed ends and its top is composed of three rows of burners 4, 5 and 6 which are separated by two 60 troughs 7 and 8, the trough 7 being separated into two parts by a partition 9, the purpose of which will appear below. The burners 4, 5, and 6 may be made in any suitable way but are preferably made of channel iron 65 with the flanges turned down and united with the base 3 and troughs 7 and 8 and the web of each channel is slotted by saw cuts 10 or in any other suitable way, as may be desired.

The partition 9 is placed in the trough 8 and divides these troughs into two parts as above stated, one of which is used to receive asbestos or any other suitable material which may be moistened by kerosene, gasoline or alcohol or any other suitable liquid and then lighted, so as to heat the incoming oil pipe 11, its double elbow 12 and the outgoing oil pipe 13 which runs from the double elbow 12 and parallel to the incoming pipe 70 11. This pipe 13 is provided with several lateral extending stems 14, 15 and 16, each of which is closed by a plug and these stems project well into the trough 8 and above the inflammable material for a purpose that will 75 appear below. The forward end of the pipe 11 is connected to an elbow 17 which runs to a regulating needle valve 18 controlled by a handle 19 and provided with a perforation 80 20 through which a hydrocarbon vapor is 85 projected into the burner tube 21.

The preheating tube 21 has three air inlets, one a hole 22 above and adjacent to the needle valve 18, one through a passage 23 at the bottom of the tube 21 and another 90 through a passage 24 which comes in at the side of the tube 21 so that any fuel projected through the needle valve 18 receives an abundant supply of air from three sides. The air is conveyed in sufficient quantities 95 to allow the fuel to mix at or near the opening 20 of the needle valve 18 and then the gas so formed passes through the horizontally disposed burner 21 and immediately 100 over the center burner 5 and thence downwardly and then forwardly and into the interior of the semi-cylinder 3 where this tube 21 is provided with three rows of perforations 25, one row being on the top and one on each side. The tube 21 is closed at its 110

front end in the chamber 3 so that the gas comes out through the openings 25 and is evenly distributed throughout the chamber and thence up through the saw slots 10 in the three burners 4, 5, and 6 where ignition occurs with even flames throughout and the heat from the center burner heats the upper portion of the tube 21 and thereby facilitates the combustion of all combustible products in the burner 21. It will be noted that the pipe 13 is adjacent to the burner 6 and is heated thereby and the pipe 11 is heated by the burner 5.

The purpose of the laterally extending tubes 14, 15 and 16 is to provide wells which will receive any liquid due to any part of the oil supply which is not vaporized in the tube 11 and elbow 12 and beginning of the tube 13 until the apparatus is in effective operation. Sometimes two of these projections say, 15 and 15 will receive some liquid and perhaps very rarely the tube 16 will receive some. Once the burner is thoroughly heated, the liquid in these projections evaporates very rapidly and none gets by them so that only vapor will issue through the opening 20 of the needle valve 18 and that will be a very hot vapor which will continue in a very hot condition because it passes through the preheating tube 21 when used as above described.

In view of the foregoing, it is hardly necessary to add, that in the embodiment of my invention just disclosed, all hydrocarbon or other fuels which may be used in the apparatus are thoroughly vaporized and then supplied with an abundant supply of air from complete combustion and then burnt, with a very hot blue flame so that the products of combustion which issue from the apparatus will contain no unburnt products.

In the foregoing has been described an embodiment of my invention which is entirely suitable for gas and coal ranges and may be used with oil as a substitute for coal or gas. It is sometimes desirable to furnish a burner which is suitable for heating hot water with kerosene instead of gas and when this is done it is accomplished as shown in Figs. 6 and 7 where the burner 26 is made cylindrical in form with saw cuts 10 at its periphery 27 and center 28 and the periphery and center are separated by a trough 29 which is provided with a partition 30 which gives the trough two ends. If desired, more

than one partition 30 may be employed. It will be understood that the periphery 27 and center 28 are at the top end of the cylinder and the bottom end is provided with a partition 31 which closes the same. Oil is supplied to the burner 26 through a pipe 32 which is curved adjacent to the trough 29 and provided with laterally extending projections 14, 15 and 16 which act as above described. The pipe 32 runs to a double elbow 12 which is connected to a pipe 33 which runs to a tube 34 which is closed at one end except for a small opening 20 which is the same as the opening of the needle valve 18 and for the same purpose. This opening 20 is in an air chamber 35 which is open at the bottom only but extends up and around the tube 34 and at the end away from this tube it is provided with a burner tube 21 which extends away from the tube 34 and then downwardly to the lower part of the cylinder 26 and thence into the cylinder as shown in Fig. 7. Its upper surface is provided with perforations 25 as above described except that the upper portion of the burner 21 is not heated.

In both embodiments of my invention the igniting or starting means is the same and once the apparatus is started, there is a complete combustion with a very hot blue flame extending through saw slots 10.

While I have shown and described some embodiments of my invention, it is obvious that it is not restricted thereto but is broad enough to cover all structures that come within the scope of the annexed claims.

What I claim is:

1. A hydrocarbon burner containing means for preheating the fuel and vaporizing the same, a perforated tube for receiving the vaporized fuel and mixing the same with air and a chamber with slotted upper walls into which the perforated tube projects so that when the burner is in use, the flames extending through the slots will heat the preheating means and the perforated tube.

2. A hydrocarbon burner provided with a chamber having an upper slotted wall and a trough and means for preheating fuel for this burner provided with laterally extending projections extending downwardly into the trough.

In testimony whereof, I have set my hand this 10 day of August, 1920.

ARTHUR E. HAUCK.
